UNITED STATES PATENT OFFICE

2,435,652

RIVETING MACHINE

Arthur F. Koehler, Yuma, Ariz.

Application June 11, 1943, Serial No. 490,542

3 Claims. (Cl. 121—9)

1

The present invention relates to new and useful improvements in riveting machines embodying a magazine feed and pneumatic means for operating the riveting hammer.

An important object of the present invention is to provide trigger controlled pneumatic means for successively moving the rivets into position and subsequently actuating the hammer to upset the rivets in the usual manner.

A further object is to provide a novel piston construction responsive to air pressure for feeding the rivets forwardly into a position at the end of the machine and also reciprocating the hammer for upsetting the rivets.

A still further object is to provide an apparatus of this character of simple and practical construction, which is efficient and reliable in performance and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which—

The figure is a longitudinal sectional view of the riveting machine.

Referring now to the drawings in detail and wherein for the purpose of illustration I have disclosed a preferred embodiment of the invention, the numeral 5 designates an air gun generally of a type designed particularly for use in upsetting rivets employed in airplane construction, the gun embodying a cylinder 6 having a handle 7 formed at the rear portion thereof and provided with a tapered plug 8 at its front end having a bore 9 therein for slidably receiving a hammer 10.

A hammer head 11 is threaded in the front end of the hammer 10 for interchangeably inserting different types of hammers for various size rivets.

A coiled spring 12 is mounted in the bore 9 for engaging a flange 13 on the hammer to retract the latter.

A hollow piston 14 is slidably mounted in the cylinder 6, the front end of the piston having a bore 15 therein slidably receiving the rear end of the hammer and the rear end of the piston is closed by a plug 16 to form a chamber 17 within the piston.

A piston 18 is formed on the rear end of the hammer 10 and is provided with a working fit in the chamber 17. The chamber 17 is provided with exhaust ports 17a and 17b at opposite sides

2

of piston 18 and a passage 17c leads from the exhaust ports to the atmosphere by way of a lateral port 6a in the cylinder 6. The rear end of the cylinder 6 is closed by a cap 19 having a chamber 20 therein and threaded through the cap is an air feed tube 21 having its inner end slidably inserted through a bore 22 and terminating in the chamber 17 behind the piston 18.

The tube 21 communicates with a chamber 23 in the handle 7, the chamber having an air intake port 24 in one side thereof and an exhaust port 32 at the rear of the chamber controlled by a valve 25 slidably mounted on a rod 26 and yieldably held against a collar 27 fixed to the rod by means of a coil spring 28. The rod 26 is slidably mounted transversely of the handle 7 and has its front end projecting forwardly of the handle for engagement by a trigger 29 pivoted to the side of the chamber 6 as indicated at 30. The rear of the chamber 23 is closed by a threaded plug 31 in which the rear end of the valve rod 26 is slidably mounted.

Formed in the handle 7 forwardly of the chamber 23 is a chamber 33 with which an air feed passage 34 communicates extending through the handle for connection with a suitable supply of air under pressure. At the forward end of the chamber 33 is a port 35 in the side of the handle to which a by-pass pipe (not shown) is connected leading to the port 24 of the rear chamber 23. The port 35 is controlled by a valve 37 secured on the rod 26 and urged into a closed position by a coil spring 38 mounted on the rod 26 within the chamber 33, the spring 38 being relatively stronger than the spring 28 so as to normally maintain the valve 37 in a closed position.

Above the chamber 33 is a chamber 39 having communication with each other through a port 40, the chamber 39 also having a port 41 in the side thereof controlled by a valve 42 secured on a rod 43 and normally closed by a coil spring 44 mounted in the chamber 39. The rod 43 extends forwardly of the handle into the path of the trigger 29 during the rearward movement thereof for actuating the valve 42.

As will be observed from an inspection of the drawing, the valve rod 26 projects forwardly of the valve rod 43 so that the former is initially actuated during the rearward movement of the trigger to open the valve 37 and close the valve 25 while a continued rearward movement of the trigger will subsequently actuate the rod 43 for opening the valve 42.

55 A tube 45 connects the port 41 with the rear

end of the cap 19 for supplying air to the chamber 20 therein, the chamber 20 having a passage 46 communicating therewith and extending through the cylinder 6 for actuating the piston 14 in a conventional manner for reciprocably actuating the piston. The piston 14 is of a type corresponding to that disclosed in Patent No. 538,433, dated April 30, 1895, and is operated substantially in accordance therewith and accordingly a detailed explanation thereof is not deemed necessary. It will be understood, however, that any improved construction may be provided for operating the piston 14 in a forward and backward reciprocating movement through the medium of air pressure supplied to the cylinder and exhausted therefrom in the usual manner.

A rivet magazine or holder 47 is removably supported on the machine by means of brackets 48 extending upwardly from the cylinder, the rivet holder being constructed of a plurality of spaced parallel rods 49 suitably arranged and open at each end for receiving and discharging the rivets 50 therefrom, the head 51 of the rivets being supported on a pair of the rods 49.

The rods 49 are secured in rigid position to each other by transverse brace members 52 as well as by hangers 53 which rise from the rods and are provided with a slot 54 in one edge thereof adapted for removably supporting the rivet holder on pins 55 carried at the upper ends of the brackets 48.

The brackets 48 are of suitable length to support the rivet holder 47 in a forwardly and downwardly inclined position and the holder is locked in position on the pins 55 of the brackets in any suitable manner.

The upper end of the rivet holder 47 is closed by a cap 57 and prior to placing the cap 57 in position a follower rivet 60 is slidably mounted on the rods behind the rearmost rivet and to the lower end of the follower rivet 60 is attached a wire or cable 61 extending forwardly under the rivet holder and around a pulley 62 and then rearwardly for winding on a spring drum 63 journaled on one of the brackets 48.

The pulley 62 is journaled on a pair of spaced parallel arms 64 extending upwardly from opposite sides of the plug 8, the arms 64 having a shaft 65 supported thereon and on which a rivet feed wheel 66 is rotatably mounted.

The wheel 66 is formed on its peripheral edge with teeth 67 adapted to engage the heads 51 of the rivets as the same drop from the front ends of the rods 49.

A rivet feed tube 68 is mounted under the wheel 66, the rear end of the tube being curved upwardly behind the wheel as shown at 69 and is split longitudinally as shown at 70 to receive the rivets through the side of the upper end of the tube. The lower end of the split 70 terminates in an upwardly and rearwardly inclined tongue 71 with which the heads of the rivets engage as the latter drop into the tube for properly positioning the rivets for feeding through the curved upper portion 69 of the tube. The tongue 71 also serves as a stop for engaging each lowermost rivet before entering the tube to prevent jamming thereof at the slot 70.

The tube 68 is pivotally supported intermediate its ends by a member 73 pivotally supported on the shaft 65 and the tube is yieldably urged downwardly at its front end by a coil spring 74 positioned between the tube and the front end of the arm 64.

The underside of the front end of the tube 68 75 32.

is formed with a discharge opening 75 for feeding the rivets to the front end of a resilient clip 76. The rear end of the clip is secured to the plug 8 by a screw 79.

5 The feed wheel 66 is provided with transverse pins 81 engageable by the front end of a reciprocating step-by-step feed member 83 connected by an eye 85 at its rear end to form a socket for swivelly mounting on a ball 86 at the upper end 10 of the trigger 29.

In the operation of the device air under pressure is admitted through the passage 34 in the handle into the chambers 33 and 39. The spring 38, being stronger than the spring 24, will normally maintain the valve 37 closed until the trigger 29 is initially moved rearwardly. The initial rearward movement of the trigger will slide the rod 26 rearwardly to open the valve 37 admitting air through the by-pass pipe 36 into the rear chamber 23, the valve 25 at the same time being moved into its closed position, to prevent escape of air through the discharge port 32.

Air is then admitted to the cylinder or chamber 17 through the tube 21 thereby forcing the piston 18 and hammer 10 forwardly to feed the rivets outwardly of the clip 76 into the usual opening provided in the work for upsetting the rivets in the usual manner.

Rivets from the holder 47 are fed into the tube 68 through the actuation of the trigger moving the rivet feeding wheel 66 in a step by step movement to discharge the rivets singly into the tube 68.

30 A spring-pressed ball 91 engages the rivet feeding wheel 66 to prevent idle rotation thereof.

Upon the forward movement of the piston 18 and hammer 10 the hammer head 11 will engage the front end of the tube 68 to pivot the latter upwardly which thereby prevents the next rivet 40 from entering the forward portion of the tube 68 during the riveting action and until the hammer 10 has been retracted by the spring 12.

During the forward movement of the piston 18 and hammer 10 air in the front end of the chamber 17 is exhausted through the bleed passage 92 formed in the hammer. This will enable the piston 18 to move more freely than the piston 14 and accordingly when air is initially admitted into the cylinder 17 the piston 18 will move forwardly 50 until it strikes the front end of the piston 14 and the pistons 18 and 14 will then move as a unit during reciprocation of the piston 14 when air is subsequently admitted through the tube 45 upon a further rearward movement of the trigger 29 to open the valve 42.

After the hammer 10 has been moved forwardly to eject the rivets through the initial actuation of the trigger 29, the subsequent actuation of the trigger will engage the rod 43 for opening the 60 valve 42 to admit air from the chamber 39 through the pipe 45 into the chamber 20 of the cap 19 where the same enters the cylinder 6 for the actuation of the piston 14 in the usual manner for reciprocably actuating the piston which thereby produces a hammer action on the hammer 10. The air entering the chamber 17 through the pipe 21 will maintain the piston 18 and hammer 10 in a forward position during the reciprocating action of the piston 14.

70 Upon releasing the trigger 29 the spring 44 will close the valve 42 while the spring 38 will close the valve 37 and open the valve 25 to permit air in the rear end of the chamber 17 to be exhausted through the pipe 21 and exhaust ports 32.

Having described the invention, what is claimed as new is:

1. A pneumatic riveting machine comprising a cylinder, a hollow piston working therein and having a bore in its rear end, a hammer having a piston integral therewith at its rear end working in the hollow piston, pneumatic means behind the second named piston to maintain the hammer in a forward position, and including a compressed air tube freely received in the bore of the hollow piston, and means for reciprocably actuating the hollow piston.

2. An air gun comprising a cylinder, a hollow piston working therein, a second piston working in the hollow piston, means for supplying fluid under pressure behind the second piston to connect the pistons for uniform movement and including a compressed air tube projecting into the rear end of said hollow piston, a hammer at the forward end of the second piston, and means for reciprocably actuating the hollow piston.

3. An air gun comprising a cylinder, interengaged pistons therein, a hammer integrally

formed with one piston, pneumatic actuating means for each piston, and a single trigger control means for said pneumatic means.
